UNITED STATES PATENT OFFICE.

GEORGE F. BIHN AND ALBERT JONES, OF PHILADELPHIA, PENNSYLVANIA.

APPARATUS FOR ELEVATING LIQUIDS.

1,373,220.

Specification of Letters Patent. Patented Mar. 29, 1921.

Application filed October 26, 1918. Serial No. 259,868.

To all whom it may concern:

Be it known that we, GEORGE F. BIHN and ALBERT JONES, citizens of the United States, residing at Philadelphia, in the county of

5 Philadelphia and State of Pennsylvania, have invented certain new and useful Improvements in Apparatus for Elevating Liquids, of which the following is a specification.

10 Our invention relates particularly to that class of apparatus which is shown and described in our United States Patent #1,191,493, granted to us July 18, 1916, and is especially directed to the valve which is 15 automatically actuated to effect the raising of liquid.

The principal objects of our invention are to provide a liquid raising apparatus with an automatically actuated valve, which is of 20 simplified construction, positive and sensitive in its action, durable and inexpensive to maintain.

Other objects of our invention are to provide a float actuated air controlling valve 25 that will not air lock and which is capable of coöperating with a check-valve of minimum capacity.

Our invention further comprehends a valve so constructed and arranged as to be 30 easily taken apart and assembled and consequently having its working parts readily accessible.

Specifically stated, the form of our invention as hereinafter described, comprises a 35 float actuated valve having opposed air inlet and outlet ports and a reciprocating piston arranged to coöperate with suitable valve seats to alternately close said air inlet and outlet ports, and having peripheral 40 guides arranged to maintain it in proper alignment to coöperate with said seats.

In the accompanying drawings, Figure 1 is a diagrammatic elevational view of a pneumatic liquid lifting apparatus, conveniently illustrating the application of our invention thereto; Fig. 2 is a vertical longitudinal sectional view taken centrally through the automatically actuated controlling valve; Fig. 3 is a plan sectional view

taken on the line 3—3 in Fig. 2; and Fig. 4 50 is a perspective view of the reciprocating valve plunger.

In said figures, the storage reservoir 1 containing the liquid to be pumped to a higher level, is connected by the pipe 2, with 55 the air pressure or blow casing 3 into which the liquid 4 in the storage reservoir 1 is permitted to flow by gravity through said pipe 2 and check-valve 5.

The outlet of the storage reservoir 1 is 60 conveniently controlled by the plug 6 which has the stem 7 guided by the bracket 8, and having at its upper end connection with the lever 9, which is fulcrumed upon the bracket 10, said lever 9 being connected by a link 65 11, having a threaded free end which is provided with a winged nut 12 adjustable in coöperative relation with the bifurcated projection 13. The rate of discharge through the pipe 2 may therefore be accurately controlled by the manipulation of said winged nut 12, as is obvious, to permit flow through 70 the pipe 2 and check-valve 5 in the direction of the arrow shown. The air pressure or blow casing 3 is a closed receptacle having 75 the pipe 15 leading from the bottom of said casing upwardly into the non-splash nozzle 16, which delivers the liquid from the casing 3 into the receiving reservoir 17.

The liquid which flows into the blow casing 3 is arranged to be forced therefrom upwardly into the receiving reservoir 17 by compressed air which is automatically controlled by the valve 19 whose casing is connected with the flanged nipple 20 leading 85 through the cover of said blow casing, and is connected with the exhaust pipe 21 having a flanged connection therewith.

The valve body 22 is preferably in the form of a disk having the annular recess 23 90 in its upper face in concentric relation with the central opening 25 which forms a conical seat 26 for the reciprocating valve plunger 27, whose depending conical projecting plug 28 is arranged to close the ports 95 29 and 30 leading into said opening 25 through the conical seat 26 from the annular groove 23, which forms the air passage

connected with a suitable source of compressed air through the opening 32 and pipe 33 connected therewith.

- As best shown in Fig. 3, the valve seat 26 is provided with a plurality of grooves or recesses 34 which permit the free escape of compressed air when the valve plunger drops into its seat 26, thus avoiding any tendency of the valve to spin or chatter.
- 10 The liquid in the blow casing may enter the valve chamber through the surge holes 31 and recesses 34, and float the valve piston off its seat as the liquid rises in the dome 38 of the valve 19.
- 15 The valve plunger 27 is provided with an annular faced upwardly projecting boss 35 arranged to coöperate with an opposed valve seat 36 surrounding the outlet 37 in the dome 38 of the valve 19 when uplifted.
- 20 by the liquid in the valve casing to seal the exhaust opening leading from said valve, so that the compressed air admitted through the thus opened ports 29 and 30 may force the liquid from the blow casing 3
- 25 through the pipe 15 to the reservoir 17.

As best shown in Fig. 4, the reciprocatory plunger 27 is formed of a central cylinder 39 having the circular flange 40 of nearly the diameter of the bore of the valve chamber and also having a plurality of radially disposed wings 42 extending in longitudinal planes and affording guides loosely engaging the wall of the dome 38, by which the valve plunger is maintained in proper 35 alignment to cause the conical projecting plug 28 and annular boss 35 to properly engage their respective seats.

Our invention is advantageous in that by providing the upper valve seat 36 of minimum area, the check-valve 5 may likewise be of minimum capacity without danger of the valve plunger becoming air locked when the liquid from the reservoir 1 flows into the blow casing 3. In other words, by reason 45 of the fact that said valve seat is of minimum area, the valve plunger responds instantly when the liquid in the blow casing has been exhausted and the pressure therein relieved, which causes the conical 50 valve plug to immediately shut off the supply of compressed air in the ports 29 and 30.

It will be seen that when the receptacle is filled, the liquid, when rising beyond the 55 uppermost part of the receptacle reaches the float of the air device. The combination of two compressed air pressures facing each other and the liquid forcing up against the bottom of the float, causes the 60 float to dislodge from its sealed seat of the apparatus. Without air pressure coming in through two port holes in the bottom seat of the air device, the liquids alone

could not raise the float and without the aid of liquid the two air pressures could 65 not lift the float. With one port hole clogged or closed off, the device in conjunction with the force of the liquid on the float, refuses to lift the float. The combination of liquid and air pressure and correct weight of float must be exact or the apparatus cannot operate. After the float seals the exhaust by means of the top seat, the liquid is forced from the device into the receptacle and the air pressure alone 70 coming through the two port holes in the bottom seat of said device causes the float in its sealed position to stay in this position until the entire contents of liquid have been forced by the two air pressures 75 through the discharge pipe to its destination.

When spent compressed air contained in the receptacle releases itself through discharge pipe of said receptacle and spent 80 compressed air in the receptacle releases, so that the air pressure remaining in receptacle is equal to the weight of the float, the float immediately drops of its own accord to the bottom seat, closing off the two compressed air ports.

It may be here noted that the valve body being constructed of a disk having an annular groove forming a compressed air passage-way, permits of the ready access 95 to the passage-ways upon removal of the dome of the valve for cleaning purposes, and affords a greatly simplified construction.

We do not desire to limit our invention to 100 the precise details of construction and arrangement herein set forth, as it is obvious that various modifications may be made therein without departing from the essential features of our invention as defined in 105 the appended claims.

Having thus described our invention, we claim:—

1. An apparatus of the class described, comprising a valve casing having inlet and exhaust ports, provided with seats, a floating valve plunger arranged to alternately close said inlet and exhaust ports, and having an annular boss coöperative with one of said seats, a conical plug coöperative with the other seat, a circular flange of slightly less diameter than the valve chamber, and a plurality of radially extended wings projecting radially beyond the periphery of said flange.

2. An apparatus of the class described, comprising a valve casing having a conical valve seat provided with ports and having passage-ways in its surface intermediate of said ports to form a by-pass into the valve 115 chamber and to relieve air pressure, and a

valve plunger having a plug coöperative with said seat to control said ports.

3. An apparatus of the class described, having a valve body comprising a valve seat, 5 ports in said seat, and an annular recess connecting said ports with a source of air supply, a dome coöperative with said body to form a casing, and a valve plunger in said casing arranged to be actuated by fluid 10 entering said casing to control said ports.

4. A valve plunger having a cylindrical core provided with a circular flange, and having a plurality of radially extending

wings projecting slightly beyond the periphery of said flange. 15

In witness whereof, we have hereunto set our hands the 12th day of August, A. D. 1918.
